(57) **CLAIM**

The ornamental design for a motorwell throughhull, as shown and described.

DESCRIPTION

The present application is related to co-dependant U.S. patent application Ser. No. 11/888,120, titled “Motorwell Throughhull,” and filed Jul. 31, 2007.

FIG. 1 is a perspective view of a first embodiment of a motorwell throughhull of our new design;

FIG. 2 is a top plan view of the embodiment of FIG. 1 thereof; FIG. 3 is a bottom plan view of the embodiment of FIG. 1 thereof;

FIG. 4 is a left side elevational view of the embodiment of FIG. 1 thereof; and,

FIG. 5 is a right side elevational view of the embodiment of FIG. 1 thereof.

Any components in the appended drawings shown in broken lines are for illustrative purposes only and form no part of the claimed design or specified embodiment thereof.
